UNITED STATES PATENT OFFICE.

IRVEN R. REEDY, OF DAYTON, OHIO.

CARBURETER.

1,044,245.

Specification of Letters Patent. Patented Nov. 12, 1912.

Application filed September 8, 1910. Serial No. 581,270.

To all whom it may concern:

Be it known that I, IRVEN R. REEDY, a citizen of the United States, residing at Dayton, in the county of Montgomery and State of Ohio, have invented certain new and useful Improvements in Carbureters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in carbureters for explosive engines adapted especially for automobiles.

The object of the invention is, first, to provide means for obtaining a homogeneous mixture of the fuel product in the carbureter, and before it passes the throttle, and second, to provide means for protecting the needle valve from undue pressure when said valve closes the gasoline orifice. In obtaining the first of these results, I submerge the lower portion of the tube in which the throttle valve is placed, and which I will term the fuel mixing tube, in an air chamber which extends up around a substantial portion of said tube. A valve-controlled side passage enters this chamber, and the submerged end of the tube acts as a baffle to break the current of air coming through this passage and to disperse it in said chamber around the sides of said tube. In addition to this air chamber, an air tube extends through said air chamber upon an incline and delivers a constant supply of air directly to the lower end of the fuel mixing tube and across the path of a jet of gasoline delivered into the lower end of said mixing tube. A more particular description of the above means follow as well as of the means through which the second object named above is accomplished.

Referring to the drawings, Figure 1 is a side elevation of my improved carbureter; Fig. 2 is a longitudinal vertical sectional elevation; Fig. 3 is a top plan view; Fig. 4 is a section on the line $a-a$ of Fig. 2; Fig. 5 is a modification showing a different form of auxiliary chamber; and Figs. 6 and 7 are detail views of portions of the needle valve controlling mechanism.

55 In the detail description of the invention similar reference characters indicate the

same parts as shown in the drawings and as described.

In the drawings, 1 indicates a tube of uniform diameter with its lower end crimped inwardly and which provides the mixing chamber. The exposed end of this tube is provided with screw threads 2 by means of which it is connected with the manifold of the engine, (not shown). The explosive mixture is formed in this tube below the throttle valve 3, which controls its passage therethrough. The said valve is mounted on a rock shaft 4 journaled in the walls of the tube and provided with a lever 5 by which the valve is manipulated. The opening movement of said valve is controlled by a projection 6 engaging the lever 5 and the closing movement thereof is controlled by an adjustable stop 7 engaging the projecting end 8 of the lever. The lower end of the mixing tube 1 is projected into and surrounded by a pocket 9 in which is located a jet 10 immediately below said tube. Also opening into said pocket 9 is an air inlet tube 11, which furnishes a constant supply of air, and an inlet 12 which furnishes a variable supply of air. The pocket 9 provides an air chamber for the quick relief of any over supply of gasoline. The communication between the mixing tube 1 and the air pocket 9 is free and unobstructed.

The tube 11 for the constant air supply is arranged upon a suitable angle with reference to the mixing tube 1 and the gasoline jet, to direct the air across the path of the gasoline as it enters below said mixing tube and to throw said gasoline together with the air against the walls of the mixing tube, and to thereby cause a thorough dispersing and mixing or vaporization. The said air tube 11 is united to the lower end of the mixing tube 1 on that side nearest the variable air inlet 12 and together with the lower end of the mixing tube 1 provides a baffle to the air entering said inlet 12. The air pocket 9 is supplied mainly through the inlet 12 and at all times furnishes sufficient air to relieve any over supply of gasoline entering the mixing tube. The suction created at the lower end of the mixing tube draws into said mixing tube any additional air from said pocket, depending upon the demands of the engine. On its outer end, the constant air inlet tube 11 is provided with a packing 14 and a nut 15, which pre-

vents the gasoline chamber from leaking. The variable air inlet 12 is provided with an inwardly opening automatic valve 16 mounted on a stem 17 attached to a yoke 18. The said valve is controlled by a conical spring 19 and a cylindrical spring 20. The conical spring controls the initial opening of the valve, and both springs control the extended movement.

- 10 The valve 16 is made of fiber so that the closing thereof is accomplished without noise. The gasoline jet 10 is supplied from the chamber 13 and is controlled by a needle valve 21, which is slidably mounted in an inclined boss 22 on the wall of the mixing tube 1. The said needle valve 21 projects out through the top of the carburetor, and is attached to a boss 23 mounted on a resilient arm 24. The portion of said needle valve which enters the boss 23 is provided with threads, and the upper end is provided with a thumb piece 25 by means of which it is adjusted to control the inlet of gasoline at the lower end of the mixing tube. The resilient arm 24 is engaged at the middle by a cam 26 on the shaft 4 of the throttle valve. The extreme end of said resilient arm is held fixed by a pin 27. When the throttle valve 3 is opened, the needle valve is also 20 opened by the resiliency of the arm 24, and when said throttle valve is closed, said needle valve is closed by the cam 26 pressing said arm 24. The closing operation of said valve is therefore accomplished through the positive action of the cam. This avoids any uncertainty in such operation of said valve which might be due to a tendency to clog, and any needless admission of gasoline is prevented. In initially adjusting said needle 30 valve, any extended movement thereof calculated to jam the needle on its seat or unduly strain the same, is avoided owing to the resilient character of the arm 24. When the engine is started and the throttle valve 3 is partially opened, gasoline will enter 40 through the jet 10 and will be intercepted by the air entering through the tube 11, as before stated. If the throttle valve 3 is opened to a greater extent, thereby increasing 45 the demand of the engine, the elevation of the needle valve 21 will allow a greater supply of gasoline, and the automatic valve 16 will supply the air pocket 9, and thus the mixture is maintained in the same proportion irrespective of the speed of the engine. The pocket 9 acts as a reservoir for the air when the throttle valve is opened quickly and the demand of the engine is increased.
- 50 The gasoline chamber 13 from which the jet is supplied, receives the gasoline from an auxiliary chamber 29 through a valve boss 30 controlled by a valve 31. The valve 31 is attached to a float 32 in the chamber 55 13 and which may be attached to a lever 33

pivoted at 34. The float 32 is buoyed by the gasoline and when the level of the gasoline is low, the said float will fall, thereby opening the valve 31 and admitting the gasoline from the upper supply chamber 29. When the chamber 13 receives sufficient gasoline, the float 32 will be elevated a sufficient extent to close the valve 31 and to thereby maintain a proper level of oil in the chamber 13.

55 In order to prime the carburetor, the chamber 13 is provided with a tubular extension 45 which receives a spring-controlled pin 46. The lower end of said pin engages a lever 33, and the upper end is adapted to be engaged by a lever 48. When said pin is pressed downward by the lever 48, the float 32 and valve 31 are also depressed, and thus the valve 31 allows the gasoline to flow from the chamber 29 to the chamber 13. The chamber 29 receives the gasoline from the main tank through a tube (not shown) attached to an elbow 47, which is in turn attached to a valve housing 34^a mounted in a casing 35 and communicating with said chamber 29 through a passage way 36. Within the housing 34^a is a valve 37, the upper end of which is attached to the end of a lever 38 projecting through the passage way 36 into the chamber 29, and which is pivoted at 39. The end of the lever 38 lying within the chamber 29, may be attached to a float 40 which, in connection with the valve 37, maintains a constant level in the chamber 29. As the chamber 29 lies between the main tank and the chamber 13, the inflow of gasoline to the chamber 13 will not be subjected to the great fluctuations in pressure due to the varying height of oil in the main tank, but will receive its supply of gasoline from the auxiliary chamber, which will be constant, owing to the presence of the float 40 and valve 37. The level of the gasoline in the chamber 13 will, therefore, always be constant, which insures an unvarying stream of oil through the jet 10 under all conditions.

90 In automobiles as usually constructed, the main tank is placed in the rear. This prevents the gasoline flowing forward when the machine is ascending a hill, especially if the supply is low. Under these conditions, the capacity of the reservoir 29 will be sufficient to meet the demands of the engine until the machine reaches the level and the gasoline flows forward.

95 The extreme bottom of the chamber 29 may be provided with a division wall or plate 41, forming a compartment 42 provided with an inlet 43 and a similar outlet, see Fig. 5. In this case the valve boss 30 extends upwardly into the plate 41. The compartment 42 may be connected with the circulating system of the engine, and the hot water passing therethrough elevates the

temperature of the gasoline, thereby allowing the gasoline to be more easily vaporized.

Means are provided for relieving chamber 13 of vapor formed above the gasoline and to thereby allow a free entrance of gasoline into said chamber to maintain a proper level therein. This means consists of a tube 44 which extends from the top of chamber 13, 10 to the upper portion of the passageway 1.

Having described my invention, I claim:

1. In a carbureter, the combination with a casing providing a gasoline chamber, and an air chamber thereabove, of a mixing tube 15 having its receiving end projected into said air chamber and having an unobstructed communication therewith, a gasoline jet projected into said air chamber below said mixing tube, a tube for the constant supply of 20 air projected into said air chamber on an angle to the plane of said mixing tube and adapted to intercept the gasoline at the mouth of said mixing tube and to direct the air and the gasoline against the interior 25 wall of said mixing tube, a tube forming a lateral passage for a variable supply of air to said air chamber, and a throttle valve located in the upper portion of said mixing tube.

2. In a carbureter, the combination with 30 a casing providing a gasoline chamber, and an air chamber thereabove, of a mixing tube, the receiving end of which is projected into said air chamber and has an unobstructed communication therewith, a throttle valve 35 in said mixing tube, a lateral tube communicating with said air chamber above the projected end of said mixing tube and providing a passage for an intermittent supply of air to said chamber, a tube projected into 40 said air chamber on an incline to the plane of the mixing tube and providing a constant supply of air, a gasoline jet projected into said air chamber below said mixing tube and adapted to deliver gasoline to said 45 mixing tube across the path of the constant air supply, a valve member controlling said jet, a resilient arm engaging said valve member to momentarily control the supply of gasoline to said mixing tube, and a cam 50 operated from the throttle valve and acting upon said arm to control said valve.

In testimony whereof I affix my signature, in presence of two witnesses.

IRVEN R. REEDY.
